ATTORNEY.

UNITED STATES PATENT OFFICE

136,660

DESIGN FOR A SCRATCH-PAD HOLDER OR SIMILAR ARTICLE

Fred H. Kiser, Los Angeles, Calif.

Application August 23, 1943, Serial No. 110,980

Term of patent 14 years

To all whom it may concern:

Be it known that I, Fred H. Kiser, a citizen of the United States, residing at Los Angeles, in the county of Los Angeles and State of California, have invented a new, original, and ornamental Design for a Scratch Pad Holder or Similar Article, of which the following is a specification, reference being had to the accompanying drawing, forming a part thereof.

The figure is a perspective view of a scratch pad holder or similar article, showing my new design.

I claim:

The ornamental design for a scratch pad holder or similar article, substantially as shown.

FRED H. KISER.
